UNITED STATES PATENT OFFICE

JOHN F. PITZ, OF NEW YORK, N. Y., ASSIGNOR TO PITZ & WEBER IRON FOUNDRY, OF NEW YORK, N. Y., A CORPORATION OF NEW YORK.

TWYER.

1,134,005.

Specification of Letters Patent. Patented Mar. 30, 1915.

Application filed April 18, 1913. Serial No. 732,402.

To all whom it may concern:

Be it known that I, JOHN F. PITZ, a citizen of the United States, residing at New York city, in the county of New York and State of New York, have invented new and useful Improvements in Twyers, of which the following is a specification.

The general object of the invention is to improve the construction of the tips of twyers, such as are used in connection with automatic stokers, in point of cheapness of manufacture, weight and assembling properties. And to this end the invention resides in forming the cover of the twyer in sections each including a plurality of tips, adapting each section and the part of the twyer on which it bears, to interlock one with the other, whereby, to effect the positioning of the whole number of nozzles in the section by the act of connecting the section itself to the part upon which it bears.

Other objects will appear and be better understood from that embodiment of my invention of which the following is a specification, reference being had to the accompanying drawings forming part thereof, in which:

Figure 1 is a sectional detail of a conventional form of automatic stoker showing my device in side elevation and in use. Fig. 2 is a detail section of the components of the cover. Fig. 3 is a detail perspective of a section of tips of the outer component of the cover. Fig. 4 is a view similar to Fig. 3 of the inner component of the cover.

In the drawings *a* indicates the table, *b* the reciprocating plunger, and *c-c* the damper rods of conventional form of automatic stoker. Inasmuch as the arrangement or construction of these elements does not form the subject matter of the present application, further description is deemed unnecessary.

d indicates the twyer shown, disposed in the ordinary manner to one side of the plunger *b*, where a plurality of such plungers *b* or other suitable feed devices, are employed and arranged as usual, in spaced relation, the twyers of course, will be as usual disposed in their proper relation, that is to say, between adjacent feed devices.

The body 5 of the twyer is formed in the usual trough-shaped structure and connects at its upper end as usual, with a source of air supply.

The cover herein designated generally by *e* is as shown in Figs. 1 and 2, made up of the inner component *f* and the outer component *g*. The latter from the exterior presents the same appearance as does the ordinary series of tips now in use with a certain class of stokers; that is to say, the tips appear as individual units, whereas, as shown in Figs. 2 and 3 these tips are included in sections one of which is shown in Fig. 2 and indicated by *h*. The section *h* as shown in Figs. 2 and 3, is a casting, but it will be understood that such section may be formed in any other desirable manner. The advantage had in forming the tips herein indicated by *h*, in a section such as is shown by *h*, over the heretofore employed method of forming the tips singly, resides in this: The section is lighter in weight than would be a corresponding number of individual tips. This difference in weight is brought about by forming the tips substantially V-shaped in contour, thereby rendering as unnecessary the solid rectangular elongation or base which would extend to the right of the extreme tip on the right in Fig. 3, to form a support for a succeeding tip, if such tip on the extreme right in Fig. 3 were cast singly. This is of great importance since, as is well-known, these tips succumb to the action of fire in a relatively short time so that when it becomes necessary to scrap the tips, which is done when the point of one or more tips is burned away, a less amount of metal will be wasted with the present structure than where the tips are individual. Then again, with the individual tip each must be formed with a locking means to interlock with the tip on which it bears and moreover, the several tips making up the cover must be separately handled to effect the assembling of the cover. With the present structure, however, it will be observed that the handling and adjusting into position of a section containing, for instance, six tips, requires no more time than does the handling of the present type of individual tip.

It will, of course, be understood that the sections may be formed with any desirable number of tips and that sufficient sections will be provided and proportioned in length so as to form a cover for the body 5 when arranged end to end, as shown. The sections may be fastened to the body 5 in any approved manner. In the drawings I

have shown an ideal arrangement in the form of the inner component *f* for connecting the sections to the body. In this arrangement the said inner component *f* is 5 suitably fastened to the sides of the body 5 by means of suitable fastening devices which pass through openings in lugs 7 depending from the sides 8 of the component *f*. This said component *f* is formed with a 10 top 9 V-shaped in cross section to conform to the cross sectional contours of the sections *h*, whose opposite sides are provided with angularly disposed elongated ports 10 which register with the ports or openings 15 11 in the front faces of the tips 6 which latter are disposed so as to direct the blast forwardly from the tips, additional outlets or ports 12 being provided on opposite sides of the points of the tips and disposed so as 20 to direct the blast in the same direction as do the ports 11. The middle portion of the top of the component *f* has slots 13 which take suitable fastening means in the form of hooks 14—14 depending from the opposite 25 site end portions of the sections *h*. With this construction it will be obvious that the several sections may be removed successively by moving the upper longitudinally of the

twyer until the hooks 14 become disengaged and permit the lifting of the section from 30 the component *f*.

What is claimed as new is:

In a twyer a section V-shaped in transverse section and having at its upper side a plurality of tips provided with openings, 35 said section being provided at its under side with integral hooks the pointed ends of which are disposed in the same direction said hooks being located along the median long dimension of the section and under the 40 apex of the angle of the V-shaped transverse configuration of the section, said hooks being disposed in a plane and the angles between said plane and the sides of the said V-shaped configuration of the section at the 45 opposite sides of said plane being of equal magnitude, the ends of the said hooks terminating short of the plane in which the side edges of the V-shaped section lie.

In testimony whereof I affix my signature 50 in presence of two witnesses.

JOHN F. PITZ.
